UNITED STATES PATENT OFFICE.

PLATON LAZARIDES, OF NEW YORK, N. Y.

LOCK.

1,273,883.

Specification of Letters Patent. Patented July 30, 1918.

Application filed December 31, 1917. Serial No. 209,615.

To all whom it may concern:

Be it known that I, PLATON LAZARIDES, residing at New York, in the county of New York and State of New York, have invented 5 certain new and useful Improvements in Locks, of which the following is a specification.

This invention relates to improvements in locks, and the present invention contemplates certain improvements over the lock 10 disclosed in my pending application Serial Number 169,192.

One of the objects of the present invention is to simplify the construction of lock 15 disclosed in the aforementioned application, so that the same may be more cheaply constructed, and whereby greater certainty of operation is obtained.

Other objects and aims of the invention, 20 more or less specific than those referred to above, will be in part obvious and in part pointed out in the course of the following description of the elements, combinations, arrangements of parts and applications of 25 principles, constituting the invention; and the scope of protection contemplated will be indicated in the appended claims.

In the accompanying drawings, which are 30 to be taken as a part of this specification, and in which I have shown a merely preferred form of embodiment of my invention:

Figure 1 is a horizontal sectional view, taken on line I—I of Fig. 2.

Fig. 2 is a vertical sectional view, taken 35 on line II—II of Fig. 1.

Fig. 3 is an elevational view, partly in section, of the parts in a different position from that shown in Fig. 2.

Fig. 4 is a sectional view taken on line 40 IV—IV of Fig. 3;

Fig. 5 is an end elevational view of the lock.

Fig. 6 is a view in elevation of the keeper.

Referring now to the drawings, wherein 45 similar reference characters refer to similar parts throughout the several views thereof, the reference numeral 1 denotes a casing, which is shown as inserted in a similarly formed aperture provided in a door 2. This 50 casing carries the usual tumbler construction employed in locks of this character, which has been generally illustrated at 3.

Provided interiorly of the casing is a shaft 4, into which the key 5 is inserted, and 55 it will be understood that when the proper key is inserted in the keyhole provided in

this shaft, the tumbler mechanism will be so operated that the shaft will be permitted to rotate, whereby the operative parts of the lock presently to be described will be operated. 60

In the present instance an arm 6, provided with a lateral extension 7, is adapted to be operated when the shaft 4 is rotated. This arm is mounted upon the shaft 4 and is 65 adapted to engage with operative parts of the lock, presently to be described, to operate the latter. It will be understood that normally the tumblers retain the shaft 4 against rotation and only permit the same 70 to be rotated when the proper key has been inserted in the lock.

The casing 1 at its outer end is provided with a head 8, the edge of which projects beyond the sides of the casing to form a shoulder or flange 9, which rests in engagement with the exterior surface of the door 2. It will be noted that this shoulder is quite narrow, and that the metal forming the same is tapered so that it is quite thin at the point 75 where the shoulder joins the head portion 9. The object of this construction is to provide such a shoulder that if an attempt be made to break the lock by inserting a lever such as a "jimmy" between the shoulder and 80 the exterior surface of the door, that the metal composing the shoulder will break away, leaving nothing for the intruder's prying implement to work against. 85

The casing 1 is provided with a rearwardly extending portion 10 provided with lateral ears 11, the latter being apertured to receive clamp screws 12 and 13 respectively. Reference numeral 14 denotes the casing which incloses the mechanism which operates the lock, said casing in the present instance being formed of a sheet metal shell, the rear wall 15 of which is provided with a struck-out rib 16 of circular formation, said rib engaging with the mouth of the 90 opening 17 of the door. The inner or rear wall 15 lies in engagement with the inner surface of the door, and the rib 16 determines the position of the same with respect to the mechanism located in the casing 1, 100 which has already been described. 105

The clamp screws 12 and 13 are inserted through apertures formed in the inner wall of the casing 15, and through the apertures in the ears 11, and are threaded into apertures 18 and 19 respectively, forming the 110 casing 1. Thus it will be seen that the

clamp screws 12 and 13 fasten together the casing 1, and the casing 14, and hold these parts in fixed relation with respect to the door, and as well said screws clamp the 5 shoulder 9 tightly against the exterior wall of the door and the wall 15 of the casing in close engagement with the inner surface of the door. The clamp screws 12 and 13 it will be noted also hold the casing 1 against 10 rotative movement within the aperture 17.

The reference numerals 20 and 21 denote plates which are located in opposed relation upon either side of the inner wall 15 of the lock casing, said plates being held together 15 as by means of rivets 22 which pass through them and which extend through an aperture 22' provided in said wall. These plates so held together are adapted to rotate within the opening 22', and extending through said 20 plates is a member 23 which is attached to the key operated shaft 4. The outer plate 21 carries the arm 6, the extension 7 which when the former is rotated, actuates the lock mechanism.

25 Thus an operative connection is provided between the shaft 4 and the arm 7, so that when the proper key is inserted in the lock a rotation thereof through the shaft 4 will cause a rotation of the arm 6, and the offset 30 portion 7 thereof will engage an operative part of the lock mechanism proper, which will presently be described.

A locking member or bolt 27 is provided, the latter having in the present instance an 35 integrally formed shaft 25, the ends of which are journaled in suitably formed bearings provided in the front wall 26 of the casing, and the rear wall 15 thereof.

The wall 26 of the casing, which carries 40 the sides, top and bottom walls of the casing, is separable from the rear wall 15 of the casing, so that the parts may be readily assembled.

The locking member or bolt 27 is substantially circular in cross section, and is semi-circular in form, the forward end 45 thereof being rounded off, as at 28. 29 indicates a web of metal, which is preferably formed integral with the arm 24 of the bolt, 50 and the bolt proper. This web fills the semi-circular space formed between the locking member, and its integrally formed shaft 25.

The locking member 27 is adapted to operate with a keeper 30 which is adapted 55 to be secured to the jamb or frame of the door, as clearly shown in Figs. 1, 3 and 6 of the drawings. This keeper has a face plate provided with an elongated slot 31, which is enlarged at its ends, as at 32 and 33, 60 as shown in Fig. 6 of the drawings. When the locking member or bolt is swung in its bearings to engage with the keeper, the rounded end 28 thereof enters the aperture 32 of said keeper, the web 29 thereof occupying the narrow space provided in the slot

31. By means of this construction it will be noted that when the locking member is swung to engage with the keeper, it is impossible for an intruder to insert an instrument between the frame and the doorway through 70 the locking member, such operation being prevented by the presence of the web 29.

Mounted upon the shaft 25 is a gear wheel 34, the teeth of which are in mesh with a gear wheel 35, which is mounted to rotate 75 upon the shaft 37 of the handle or knob 37', said shaft extending through an aperture provided in the outer wall of the lock casing, said shaft being rotatably mounted in said aperture. Keyed or otherwise fastened 80 to the shaft 37 is a plate 38, said plate being provided with an arm 38' and with a slot 38''. Arm 38' when plate 38 is rotated in the direction of the arrow, as by means of the knob 37', is adapted to engage with a pin 39 carried upon the gear wheel 35, and which extends laterally therefrom, so that gear wheel 35 will be impelled to rotation, thereby rotating the gear wheel 34 in mesh therewith and operating the bolt 27.

Interposed between a post 41 which is formed by a struck-up part of the plate 38, and a pin 42 extending inwardly from the front wall 26 of the casing, is a retractile spring 43, the function of which is to urge 95 the gear wheel 35 into rotation in a direction contrary to that shown by the arrow in Fig. 2, whereby the gear wheel 34, and the locking member 27, at all times have a bias or tendency to rotate in such a direction 100 that the locking member will be urged to movement into engagement with its keeper.

The reference numeral 44 denotes a detent which is pivotally supported upon the pivot screw 45. The outer end of this detent is 105 provided with an offset or upstanding portion 46, which is adapted to engage with the outer end of the arm 24 of the locking member, so that when the parts are in a position shown in Fig. 2 of the drawings, the engagement of this detent with said arm prevents the locking member or bolt from being swung in the direction indicated by the arrow. 47 indicates a spring, preferably to be formed of spring wire, which encircles the 110 pivot pin 45, and which co-operates with a fixed pin 48 carried by the front wall of the casing to hold the detent 44 in its normal position, said pin 48 also operating as a stop to limit the inward swinging movement of 115 the detent. Mounted upon the detent is a pin 49, and this pin is in engagement with the end 50 of the spring 47, and the arm 50' of said spring, whereby by which engagement the spring performs its function upon 120 the detent. The end 50 of the spring 47 is located in the path of a post 51, which is formed by a struck-up portion of the arm 38' of the plate 38, so that when said plate is rotated the post 51 will engage the outer 125

end 50 of said spring 47, whereby the engagement of said end 50 through the post 49, will swing the detent outwardly, thereby carrying the offset portion thereof out of the path of the arm 24 of the locking member, so that the latter may be retracted. It will be noted that by reason of the provision of the slot 38' and the plate 38, a free initial movement of the plate 38 may be had before there is any rotation of the gear wheel 35, by means of the engagement therewith of the arm 38'. This permits the post 51 to engage the end 50 of the spring 47 and move the detent 44 rearwardly out of the way of the locking member or bolt before the gear 35 commences to rotate the gear wheel 34.

Mounted to slide in a suitable casing 53, carried by the wall 26 of the casing, is a latch member 54. This latch member is adapted to effect an actuation of the locking mechanism in a manner which will be hereinafter described. The reference numeral 55 indicates a lever, one end of which is provided with legs 55' which straddle the inner end of the casing 53, the part of said lever between said legs being adapted to be engaged by the latch member 54. Lever 55 intermediate its ends is provided with an elongated slot 56, through which extends a pivot screw 57, said screw connecting the intermediate portion of the lever with a slide 58 provided with an operating button 59, which extends laterally therefrom and through an elongated opening 60 provided in the outer wall of the casing. Slide 58 is provided with the upstanding pins 61 and 62, which coöperate with portions 63 and 64 of a spring 65, the intermediate portion of which encircles a screw 66, the end of which is threaded into the outer wall of the casing, and said screw extending through an elongated slot 67 provided in the slide 58.

It will be seen when the slide 58 is moved inwardly or outwardly, as by means of the button or handle 59, the coöperation between the pins 61 and 62 with the portions 63 and 64 of the spring 65, will hold said slide in either of two positions, from one to the other of which it can be moved against the tension of said spring.

The outer end 68 of the lever 55 is adapted to be moved adjacent the outer end of a pin 69 carried upon the pawl 70, the latter being pivoted upon a screw 71, so that the end of the pawl may be swung into or out of engagement with the teeth upon the gear wheel 35; a spring 72 operating between the end wall of the casing and the pawl, normally urging the latter into engagement with said gear teeth.

It will be seen that when the pawl 70 is in engagement with the teeth of the gear 35, as indicated in Fig. 3 of the drawings, said gear wheel is prevented from being ro-

tated in the direction which it is at all times urged by means of the retractile spring 43. But when said pawl is moved from engagement with such teeth said gear wheel is permitted freely to rotate under the influence 70 of said spring. It will be also seen that the lever 55 is adapted to establish an operative connection between the latch member 54 and the pawl, when said lever is in the position indicated in Fig. 2 of the drawings, 75 and that lever 55, when moved outwardly as by means of the slide 58, will be moved into such a position that the end 68 thereof will clear the pin 69 mounted upon the pawl 70.

The latch member 54 has its outer end projecting through the inner wall of the casing of the lock, so that when the door is closed the outer end of said latch will engage with the keeper, the outer end of 85 said latch member being beveled off, as at 73, so that when such engagement takes place the latch member will be forced inwardly, whereby the engagement of the inner end of the latch member will cause 90 an endwise movement of the lever 55. Therefore, if the lever 55 is in such position that the end 68 thereof will engage the pin 69 of the pawl 70, the latter will be disengaged from the teeth of the gear wheel 35, 95 whereby the latter will be rotated under the influence of the spring 43. However, if the slide 58 has been manipulated to move the end 68 of the lever 55 outwardly, whereby it will clear the end of the pin 69 of the 100 pawl 70, an inward movement of the latch 54 within its casing will not disturb the operative relation of said latch 70 with the teeth of said gear wheel 34.

The offset portion 7 of the arm 6 is adapted to engage with a post 74 formed by a struck-up portion of the plate 38, so that when the proper key is inserted in the lock, permitting the shaft 4 to be rotated, the rotation of said shaft 4, carrying the arm 6 110 and its offset portion 7 therewith, will cause the latter to engage with the post 74, whereby the plate 38 will be rotated in identically the same manner as it will be rotated by means of the handle or knob 37'. Thus the 115 lock is actuated in the same manner from either the outside or the inside, although the means for actuating the lock from the inside or the outside of the door are independent of each other.

The reference numeral 75 indicates a pin carried by a knob or handle 76, said pin operating in a slot 77 formed in one of the side walls of the casing. This pin when slid to one end of the slot is adapted to form a stop 125 for the detent 44, whereby it will be impossible to swing the latter outwardly to carry it from out of the path of the bolt. The pin 75 when moved to the other end of the slot will clear the arm 46 of the detent, whereby 130

the latter will be free to swing out of the path of the bolt 27, thus permitting the latter to be swung to its unlocked position. A spring 78 mounted upon the screw 79 operates to hold the pin 75 in position at either end of the slot.

Mounted upon the inner wall 15 of the casing and extending inwardly thereto, is a pin 80. This pin forms a stop for said arm and permits only the rotation of the key of the lock in a predetermined direction.

Having thus described the construction of this embodiment of my invention, the operation thereof may now be understood.

Assuming the parts to be in the position shown in Figs. 1 and 2 of the drawings, with the bolt in locking position within its keeper, a rotation of the handle or knob 37' 20 will cause the plate 38 to be rotated, whereby upon the initial rotative movement thereof the post 51 of the arm 38' will first engage with the end 50 of the spring 47, thereby causing the latter to swing the detent 44 out 25 of the path of the bolt 27. The arm 38' will then engage with the pin 39 of the gear wheel 35, so that during a continued rotative movement of the plate 38 the gear 35 will move with it, thereby causing the gear 30 wheel 35 to rotate and moving the locking member or bolt from the position shown in Figs. 1 and 2 to the position shown in Fig. 3, where it is held by means of the engagement of the pawl 70 with the teeth of the gear wheel 35. With the parts in this position the door is unlocked and is free to be opened.

Assuming the parts to be in the position shown in Fig. 3; it will be seen that when 40 the door is closed, and the latch 54 moved inwardly, the end 68 of the lever 55 will clear the pin 69 of the pawl 70, and the closing of the door therefore will have no effect upon the lock.

Assuming, however, the lever 55 to have 45 been moved into the position shown in Fig. 2 of the drawings, the engagement of the beveled end 73 of the latch 54 with the face of the keeper, will force the latch 54 inwardly as before, but inasmuch as the lever 55 has been moved so that it will engage the pin 79 of the latch 70, this operation will 50 carry the pawl 70 from its engagement with the teeth of the gear wheel 35, thereby permitting the retractile spring 43 to move the plate 38, so that the engagement of the wall of the slot 38' with the pin 39 will rotate the gear wheel 35, and through the operative connection of the latter with the gear 34, 55 the locking member will be swung into engagement with its keeper and the door locked.

Thus it will be seen that with the parts 60 in the last described position, whenever the lock is operated to unlock the door and the

door is subsequently closed, the bolt will be automatically moved to its locking position by means of the engagement of the latch 54 with the face of the keeper through the operative connection which has been described.

When it is desired to place the lock in such condition that it cannot be opened by either a key inserted from the outside, or by the handle or knob 37', it is merely necessary to slide the pin 75 to the forward end of the slot, whereby it will be moved into the path of the arms 46 of the detent 44, whereby the latter will be prevented from such swinging movement as will carry it out of the path of the bolt. Attempted operation of the bolt, therefore, either by a key or by the handle, will be arrested by means of this pivoted detent.

It will be noted that when the parts are 35 in the position shown in Figs. 1 and 2 of the drawings, the operation of the retractile spring 43 will always hold the plate 38 in such position that it is behind the end 50 of the spring 47, whereby the post 51 thereof 40 will engage with the end 50 of said spring whenever the lock is actuated either by a key from the outside, or by means of the handle or knob 37'. Thus the parts are always in position whereby the bolt may be 45 retracted either by a key or by manipulation of said handle or knob.

It will accordingly be seen that I have provided a construction which is well adapted to attain, among others, all the ends and 100 objects above pointed out. The lock, although simple in construction, is strongly constructed and is certain in operation. Inasmuch as many of the interior parts of the lock are formed of a sheet metal, these parts 105 can be constructed by means of a stamping operation, thus diminishing the cost of producing the lock. The provision of the web in the locking member prevents the door from being pried open by an instrument inserted between the jamb and the edge of the door. Moreover, the lock being of such construction that it may be set for automatic 110 operation, the door will be automatically locked without any attention on the part 115 of the occupant of the building or dwelling upon the door of which the lock is mounted.

As many changes could be made in this construction without departing from the scope of the following claims, it is intended 120 that all matter contained in the above description or shown in the accompanying drawing shall be interpreted as illustrative only and not in a limiting sense.

Having thus described my invention what 125 I claim as new and desire to secure by Letters Patent is:

1. A lock comprising a casing adapted to be secured to a door, a keeper adapted to be secured to the frame, a pivotally mounted 130

arc shaped bolt mounted within the casing, and adapted to engage with the keeper, a gear wheel operably connected with said bolt, a driving gear wheel meshing with said 5 first named gear wheel, an actuating member for said last named gear wheel having a loose connection therewith, key controlled means for operating said actuating member, and a spring interposed between a fixed 10 support within the casing, and said actuating member adapted through the latter normally to urge said bolt into engagement with its keeper.

2. A lock comprising a casing adapted to 15 be secured to a door, a keeper adapted to be secured to the frame, a pivotally mounted arc shaped bolt mounted within the casing and adapted to engage with the keeper, a gear wheel mounted upon the shaft of said 20 bolt, a driving gear wheel meshing with said first named gear wheel, an actuating member for said second named gear wheel mounted concentrically therewith, said actuating member having a limited independent movement relative to the second named gear 25 wheel, and said gear wheel and said actuating member having means which engage after such limited relative movement between the aforesaid parts, whereby there- 30 after they move in unison, means extending into said casing from opposite directions, each of which is adapted independently to operate said actuating member, and spring means extending between a fixed point in 35 the casing and said actuating member, which is adapted to hold the latter in normal position, and through the latter and the connec- 40 tions between said bolt to urge said bolt into locking engagement with its keeper.

40 3. A lock comprising a casing adapted to be secured to a door, a keeper adapted to be secured to the frame, a pivotally mounted arc shaped bolt mounted within the casing and adapted to be rotated into engagement 45 with the keeper, a gear wheel mounted upon the shaft of said bolt, a second gear wheel journaled within said casing, which meshes with said first named gear wheel and drives the same, a plate mounted concentrically of 50 said second named gear wheel, said plate and said second named gear wheel being so mounted with respect to each other that they have a limited independent relative movement, means upon said second named gear 55 wheel and said plate adapted to engage with each other after such relative movement, whereby thereafter said plate will drive said gear wheel, and actuating means extending into said casing from opposite directions 60 which are adapted independently to operate said plate.

4. A lock comprising a casing adapted to be secured to a door, a keeper adapted to be secured to the frame, a pivotally mounted arc 65 shaped bolt mounted within the casing and

adapted to be rotated into engagement with the keeper; a gear wheel mounted upon the shaft of said bolt, a second gear wheel mounted within said casing and having a driving connection with said first named gear wheel, 70 an actuating plate mounted concentrically of said second named gear wheel and having a limited relative movement with respect thereto, co-operating means upon said second named gear wheel and said plate for determining 75 the extent of said limited relative movement, a spring interposed between a fixed point within the casing and said plate which normally holds the latter in such position that with the interposed connection between the 80 same and the bolt the latter is urged into engagement with the keeper, and means extending into said casing from opposite directions, each of which is adapted independently to actuate said plate, whereby the latter will retract said bolt from engagement with the keeper.

5. A lock comprising a casing adapted to be secured to a door, a keeper adapted to be secured to the casing, a pivotally mounted 90 arc shaped bolt mounted within the casing, which is adapted to engage with the keeper, a member journaled within said casing having an operative connection with said bolt, adapted to move the latter into and out of 95 engagement with its keeper, actuating means for said member which is capable of independent relative movement with respect thereto, interposed means upon said member and upon said actuating means whereby 100 after an initial relative movement said elements move in unison, and a spring interposed between a fixed point within the casing and said actuating means which normally holds the parts in such position that 105 the bolt is urged into engagement with its keeper.

6. A lock comprising a casing adapted to be secured to a door, a keeper adapted to be secured to the casing, a pivotally mounted 110 arc shaped bolt mounted within the casing, which is adapted to engage with the keeper, a member journaled within said casing having an operative connection with said bolt, adapted to move the latter into and out of 115 engagement with its keeper, actuating means for said member which is capable of independent relative movement with respect thereto, interposed means upon said member and upon said actuating means whereby 120 after an initial relative movement said elements move in unison, a spring interposed between a fixed point within the casing and said actuating means which normally holds the parts in such position that the bolt is urged into engagement with its keeper, and independent means which extend into said casing from opposite directions, each of 125 which is adapted independently of the other to operate said actuating means, one of said 130

last named means being key operated from the outside of the door.

7. A lock comprising a casing adapted to be secured to a door, a keeper adapted to be secured to the frame, a revolvably mounted arc shaped bolt within the casing adapted to be revolved into engagement with the keeper, a gear wheel mounted upon the shaft of said bolt, an actuating gear wheel journaled within said casing, a slotted actuating plate mounted concentrically of said second named gear wheel, a pin mounted upon said second named gear wheel and extending through the slot of said actuating plate, said slot being of such width that said actuating plate and said second named gear wheel are capable of relative angular movement with respect to each other, so that said plate may be moved in opposite directions relatively 20 to the gear wheel until the walls of the slot engage with said pin, a spring extending between said plate and the fixed point within the casing adapted to urge said plate into rotative movement in such direction that the 25 bolt through its operative connection therewith will be urged into engagement with its keeper, and means extending into said casing from opposite directions, each of which is adapted independently of the other to 30 actuate said plate.

8. A lock comprising a casing adapted to be secured to a door, a keeper adapted to be secured to the frame, a revolvably mounted arc shaped bolt within the casing adapted 35 to be revolved into engagement with the keeper, a gear wheel mounted upon the shaft of said bolt, an actuating gear wheel journaled within said casing, a slotted actuating plate mounted concentrically of said second 40 named gear wheel, a pin mounted upon said second named gear wheel and extending through the slot of said actuating plate, said slot being of such width that said actuating plate and said second named gear 45 wheel are capable of relative angular movement with respect to each other, so that said plate may be moved in opposite directions relatively to the gear wheel until the walls of the slot engage with said pin, a spring 50 extending between said plate and the fixed point within the casing adapted to urge said plate into rotative movement in such direction that the bolt through its operative connection therewith will be urged into engagement 55 with its keeper, means extending into said casing from opposite directions, each of which is adapted independently of the other to actuate said plate, a pivotally mounted detent which normally prevents 60 said bolt from being retracted, and means carried by said plate which is adapted to move said detent out of the path of the bolt upon an initial movement of the plate with respect to the gear wheel, whereby the 65 bolt may be thereafter retracted.

9. In a device of the type described, in combination a lock, a keeper therefor, said lock including a pivotally mounted arcuate bolt in normally spring-urged engagement with said keeper and having an arm extending in a right-line from its pivot at the center of the circle of which said bolt is an arc, said bolt being formed with a web filling in the space intermediate said arm and the arc of said bolt, means adapted to normally prevent the retraction of the bolt, actuating means for said bolt including a pivotally mounted latch adapted to engage said bolt actuating means and hold the bolt in retracted position, and movable means adapted to engage said keeper when the door is closed for releasing said latch from said actuating means.

10. A lock comprising, in combination, a casing adapted to be mounted upon a door, and a keeper adapted to be secured to the frame of the door, a bolt pivotally mounted in said casing and adapted to be engaged by the said keeper, means which normally urges the bolt into engagement with the keeper, means adapted normally to prevent the retraction of the bolt, actuating means for said bolt, including a pivotally mounted latch adapted to engage said bolt-actuating means and hold the bolt in retracted position, and movable means adapted to engage the keeper when the door is closed for releasing said latch from said actuating means.

11. A lock comprising a casing adapted to be secured to a door, a keeper adapted to be secured to the frame, a pivotally mounted arc-shaped bolt mounted within the casing, which is adapted to engage with the keeper, resilient means for normally urging the bolt into engagement with the keeper, actuating means for said bolt, a plurality of operating means extending into the casing from either side, each of which is adapted independently to retract the bolt, a pivotally mounted catch adapted to engage the actuating means and hold the bolt in retracted position, and movable means adapted to engage with the keeper when the door is closed, whereby said catch will be released from the actuating means, and the bolt will automatically move into engagement with the keeper.

12. A lock comprising a casing adapted to be secured to a door, a keeper adapted to be secured to the frame, a pivotally mounted arc-shaped bolt mounted within the casing, which is adapted to engage with the keeper, resilient means for normally urging the bolt into engagement with the keeper, actuating means for said bolt, a plurality of operating means extending into the casing from either side, each of which is adapted independently to retract the bolt, a pivotally mounted catch adapted to engage the actuating means and hold the bolt in retracted position, movable means adapted to engage with the

keeper when the door is closed, whereby said catch will be released from the actuating means and the bolt will automatically move into engagement with the keeper, and manually operable means for determining the operation of said last named movable means.

13. A lock comprising a casing adapted to be secured to a door, a keeper mounted upon the door frame, a pivotally mounted arc-shaped bolt located within said casing, resilient means normally urging said bolt into engagement with said keeper, actuating means for said bolt, a pair of independently operative means extending into said casing from opposite sides, each of which is adapted independently to operate said actuating means, a pivotally mounted detent having a freely projecting resilient member, a key actuated shaft provided with an arm adapted to engage said resilient member and having an offset adapted to engage said locking bolt, each of the means employed to operate the actuating means being adapted when operated first to move said detent and then retract said bolt.

14. A lock comprising a casing adapted to be secured to a door, a keeper mounted upon the door frame, a pivotally mounted arc-shaped bolt located within said casing, resilient means normally urging said bolt into engagement with said keeper, actuating means for said bolt, a pair of independently operative means extending into said casing from opposite sides, each of which is adapted independently to operate said actuating means, a pivotally mounted detent which normally prevents the bolt from being retracted, each of the means employed to operate the actuating means being adapted when operated first to move said detent and then retract said bolt, and a pivotally mounted catch adapted to engage said actuating means to hold said bolt out of engagement with said keeper.

15. A lock comprising a casing adapted to be secured to a door, a keeper mounted upon the door frame, a pivotally mounted arc-shaped bolt located within said casing, resilient means normally urging said bolt into engagement with said keeper, actuating means for said bolt, a pair of independently operative means extending into said casing from opposite sides, each of which is adapted independently to operate said actuating means, a pivotally mounted detent which normally prevents the bolt from being retracted, each of the means employed to operate the actuating means being adapted when operated first to move said detent and then retract said bolt, a pivotally mounted catch adapted to engage said actuating means to hold said bolt out of engagement with said keeper, and a plunger extending outwardly from said casing adapted to engage the keeper when the door is closed,

whereby said catch will be moved out of engagement with said actuating means, permitting the bolt to move into engagement with said keeper.

16. A lock comprising a casing adapted to be secured to a door, a keeper mounted upon the door frame, a pivotally mounted arc-shaped bolt located within said casing, resilient means normally urging said bolt into engagement with said keeper, actuating means for said bolt, a pair of independently operative means extending into said casing from opposite sides, each of which is adapted independently to operate said actuating means, a pivotally mounted detent which normally prevents the bolt from being retracted, each of the means employed to operate the actuating means being adapted when operated first to move said detent and then retract said bolt, a pivotally mounted catch adapted to engage said actuating means to hold said bolt out of engagement with said keeper, a plunger extending outwardly from said casing adapted to engage the keeper when the door is closed, whereby said catch will be moved out of engagement with said actuating means, permitting the bolt to move into engagement with said keeper, and selected means adapted to connect said plunger with said catch.

17. A lock comprising a casing adapted to be secured to a door, a keeper mounted upon the door frame, a pivotally mounted arc-shaped bolt located within said casing, resilient means normally urging said bolt into engagement with said keeper, actuating means for said bolt, a pair of independently operative means extending into said casing from opposite sides, each of which is adapted independently to operate said actuating means, a pivotally mounted detent which normally prevents the bolt from being retracted, each of the means employed to operate the actuating means being adapted when operated first to move said detent and then retract said bolt, a pivotally mounted catch adapted to engage said actuating means to hold said bolt out of engagement with said keeper, a plunger extending outwardly from said casing adapted to engage the keeper when the door is closed, whereby said catch will be moved out of engagement with said actuating means, permitting the bolt to move into engagement with said keeper, and manually controlled means adapted when in one position to connect said plunger with said catch, and when in another position to operatively disconnect said elements.

18. A lock comprising a casing adapted to be secured to the door, said casing containing the lock mechanism, a keeper adapted to be locked to the frame of the door, a casing which extends through the door and which contains the tumbler mechanism

which determines the operation of the lock, said last named casing being provided with a key-receiving head which rests against the outside of the door, and said head having a 5 frangible head engaging the exterior surface of the door.

19. A lock comprising a casing adapted to be mounted upon a door, a keeper mounted upon the frame of the door, said keeper having an elongated slot the intermediate portion of which is restricted, and having enlarged end shaped portions, a pivotally mounted arc-shaped bolt mounted within said casing, which is adapted to engage 10 with said keeper, the rim of said bolt engaging the enlarged opening, and said bolt having a web which extends into the restricted portion of said slot, spring means for normally urging said bolt into engage- 15

ment with said keeper, independently operable means for retracting the bolt, means which normally prevents the bolt from being retracted, pawl and ratchet mechanism for holding the bolt in retracted position, a flange carried by said casing which is adapted 20 to engage said keeper when the door is closed, to release said pawl and ratchet mechanism, whereby the bolt will be automatically moved to locking position, and manually operated selected mechanism 25 adapted to connect or disconnect the plunger with said pawl and ratchet mechanism.

In testimony whereof I affix my signature in the presence of two witnesses.

PLATON LAZARIDES.
